UNITED STATES PATENT OFFICE.

CHARLES STERN, OF JERSEY CITY, NEW JERSEY, AND RICHARD WALLACE BRADEN, OF NEW YORK, N. Y., ASSIGNEES TO B. & S. MANUFACTURING PRODUCTS CORPORATION, OF JERSEY CITY, NEW JERSEY, A CORPORATION OF NEW JERSEY.

ATTACHMENT FOR LOCOMOTIVES.

Application filed August 8, 1921, Serial No. 490,605. Renewed October 21, 1926.

The present invention relates to improvements in attachments for locomotives, and more particularly refers to an improved device for effectively lubricating the cylinders of a locomotive, and at the same time serving to break the vacuum in the cylinders while the locomotive is drifting or coasting with the throttle closed.

No small trouble and annoyance has been experienced heretofore in the proper lubrication of the internal parts of locomotive cylinders and faulty lubrication has resulted in the frequent necessity for renewing piston rings, removing carbon, and otherwise repairing the pistons and scored cylinder walls. Moreover, it is desirable to insure the flow of lubricant not only when the engine is operating under steam, but also when drifting or coasting with the throttle closed.

It is an object of the present invention to accomplish the accurate and timely lubrication of locomotive cylinders by a device which will at the same time operate to relieve the vacuum which the traveling pistons tend to create in the cylinders when the engine is coasting or drifting, and which will furthermore serve to furnish lubricant to the internal parts whenever the locomotive is in motion without regard to whether it be drifting or moving under steam.

Another object of the invention is to provide a device for carrying out the above described purposes in a simple yet faithful manner, and wherein the device is of a simple and inexpensive structure and is so built up as to be capable of installation upon locomotives of present types without any material alteration therein.

A still further object of the invention is to provide means so that steam will cushion the steam pistons and their reciprocating parts in the steam cylinders and keep the super-heated units moist while the locomotive is coasting or drifting.

With the foregoing and other objects in view, the invention will be more fully described hereinafter, and will be more particularly pointed out in the claims appended hereto.

In the drawings, wherein like symbols refer to like or corresponding parts throughout the several views.

Fig. 1 is a top plan view of an apparatus

constructed according to the present invention with a portion thereof broken away;

Fig. 2 is a vertical sectional view taken on the line 2—2 in Fig. 1;

Fig. 3 is a horizontal sectional view taken on the line 3—3 in Fig. 2;

Fig. 4 is a similar view taken on the line 4—4 also in Fig. 2;

Fig. 5 shows a sectional view taken on the line 5—5 in Fig. 2;

Fig. 6 is an enlarged fragmentary sectional view through the check valve and balance passage taken on the line 6—6 in Fig. 7;

Fig. 7 is a sectional view taken on the line 7—7 in Fig. 6;

Fig. 8 is also a vertical sectional view taken at a different angle compared to Fig. 2 and showing the parts in a subsequent position;

Fig. 9 is a diagrammatic view showing the device in connection with a lubricant tank and the locomotive cylinder and steam chest.

Referring more particularly to the drawings, and for the present to Figs. 1 to 8 inclusive, 1 designates a shell or casing having an internal barrel 2 centrally therein and with its axis disposed vertically and surrounded by an annular chamber 3 of substantially great capacity which has a threaded nipple 4 extending from the lower portion thereof at one side to connect, as by means of a coupling nut 5, with a pipe section 6 which receives steam from the steam dome or other suitable source of supply. At the lower portion of the barrel 2 diametrically aligning perforations 7 and 8 are made to put the steam pipe 6 and the annular chamber 3 in communication with a passage 9 which extends downwardly at one side of the shell 1 and communicates at its lower part with a conduit 10 made in a coupling head 11, which is bolted or otherwise secured to the bottom of the shell 1. The coupling head 11 also carries an extension 12 adapted to receive a suitable coupling for placing the passage 9 and the conduit 10 in communication with a similar apparatus which is situated at the other side of the locomotive and acts in conjunction with the cylinder and steam chest at that side.

The devices may, however, be entirely independent, in which case the extension 12

may be dispensed with or plugged. In the lower central portion of the shell 1 beneath the barrel 2 and coaxial therewith is a cylinder 13 of an enlarged diameter as compared with the bore of the barrel 2 and having a piston 14 therein reciprocating vertically and adapted to mask, when in the upper position, a port 15 in the side wall of the cylinder 13 which communicates with the passage 9. In a similar way, at its lower position as shown in Fig. 8, the piston 14 is adapted to close a port 16 entering the lower portion of the cylinder and leading to a vertically extending passage 17 formed in an enlargement 18 at the side of the shell 1 and preferably integral therewith.

The passage 17 extends up to an enlarged head 19 formed at the top of the shell 1 and providing therein a dome to receive steam through the passage 17. The passage 17 is shown as provided with a check valve, such as 20, disposed upon the upper end of a stem 21 which lies through a coil spring 22 located in a cylindrical thimble 23 which repose in a suitable enlargement at the top portion of the passage 17. The lower end of the stem 21 is threaded and receives a nut or washer 24 which takes against the lower end of the coil spring 22. A threaded seat 25 is provided just beneath the disc valve 20 and is threaded into the upper end of the passage 17. The nut or washer 24 is preferably provided with arms, as indicated in Fig. 6, in order to catch the spring but at the same time afford ample opportunity for the fluid to pass upwardly through the passage and into the head 19. The valve, its spring, and appurtenant parts form a unitary construction which may be removed as a whole from the passage by unscrewing the head 25. The valve 20 opens upwardly under the influence of a pressure in excess of that developed by the spring 22, which may accordingly be selected to control the opening of the valve 20. The valve, of course, seats automatically and prevents any back pressure from getting down into the passage 17.

The space within the head 19 communicates with an upper cylinder 26 which is of substantially the same dimensions as the cylinder 13 and is occupied by a vertically reciprocating piston 27 which, in its upper position, as shown in Fig. 2, closes an exhaust port 28 which may lead to the atmosphere directly. The upper piston 27 is connected to move in unison with the lower piston 14 and to effect this result a stem 29 is provided to extend through the barrel 2 and to accurately fit the same so that it may slide back and forth vertically with the pistons 14 and 27.

The stem 29 is provided with an axial bore 30 communicating at its central part with a transverse duct 31 adapted to register with oil passages 32 and 33 which extend through

the walls of the shell 1 and also through the cylindrical wall of the barrel 2 and are adapted to be put in communication by the transverse duct 31 when the valve stem 29 is in the raised position shown in Fig. 2. Oil is also permitted to descend from the transverse duct 31 into the vertically disposed bore 30, and for the purpose of distributing a sufficient quantity of lubricant to the lower cylinder 13 there are provided a number of downwardly divergent eduction ports 34 which lead to the exterior of the stem 29 and down into the cylinder 13 when the piston 14, for instance, is in a low position, the lower part of the barrel 2 serving to close the eduction ports 34 when the piston 14 is raised.

Below the transverse port 31 the stem 29 is cut away forming an annular channel 35 which, as indicated in Fig. 8, is brought opposite the ports 7 and 8 when the pistons are lowered and affords a communication between the steam pipe and steam chamber 3 and the passage 9. At its upper end the stem 29 is provided with a rod or spindle 36, screw threaded or otherwise removably engaged therewith as indicated at 37, and having a conical tip 38 seating against a complementally formed seat in the spindle bore. This spindle 36 may be removed for purposes of gaining access to the bore of the stem whereby the cleaning out of the same may be expeditiously effected. The upper end of the spindle or rod 36 extends upwardly and movably through a bearing 39 threaded into a cap piece 40 which is screw threaded into the upper portion of the head 19. The upper end of the spindle or rod 36 can be seen by the engineer at his position in the cab so that he may know whether the valves 14 and 27 are in the upper or lower position and may be apprised as to whether oil and steam are being fed to the cylinders or not.

A branch passage 41 extends diagonally of the stem 29, communicating at its inner end with the bore 30 and at its outer end opening through the side of the stem above the transverse passage 31 and being adapted, when the stem and valves are lowered, to come into registry with the passage 32 in which position oil will flow from the passage 33 through the passage 41 into the bore 30. One or more perforations 42 are provided in the head of the lower cylinder 13 to set up a communication between the upper portion of the cylinder and the annular chamber 3. In like manner a number of perforations 43 are provided in the lower head of the upper cylinder 26 to place the lower side of the piston 27 in connection with the steam chamber 3.

Referring to Fig. 9, the conduit 10 which leads from the base of the shell 1 is shown communicating with the steam chest 65.

which is disposed just above the locomotive cylinder indicated diagrammatically at 66 and having the pet cock 67 to which the cylinder may be turned. At 68 there is represented the usual steam intake pipe for furnishing a supply of steam under control of the throttle valve from the steam dome to the steam chest 65. An oil pipe 69 is shown as connecting the steam supply pipe 68 with the passage 33 of the shell 1 and a further pipe 70 is shown as connecting with the opposite oil channel 32 in the shell 1. This pipe 70 is arranged at an inclination and communicates at its upper end with a source of lubricant supply 71 which feeds downwardly by gravity. The oil passages 32 and 33 are shown as passing substantially horizontally through the shell 1.

In the operation of the device the oil flows from the lubricator 71 to the drifting device. This reservoir 71 is the usual oil reservoir found on all locomotives and the oil is subjected in the customary way to a steam pressure of approximately two hundred pounds, the steam driving the oil down through the drifting device.

During the running of the locomotive with the throttle open the parts are in the position shown in Figure 2 so that the port 31 registers with the passages 32 and 33 and forms a through way for the oil from the lubricator to the pipe 69 which connects with the steam supply pipe 68 to the locomotive steam chest 65. When the throttle is open and the locomotive in motion, the steam chest pressure gets up beneath the lower piston 14 and moves the parts upwardly to the extent shown in Figure 2.

In this it is assisted by the saturated steam pressure getting from the central chamber 3 through the ports 43 to the under side of the larger piston 27. In this position the lubricant is fed at all times to the locomotive parts as just explained. Moreover the piston 14 in the upper position exposes the port 16 to the steam pressure, the steam passing up through the passage 17 as shown in Figure 8 and raising the non-return check valve 20. This permits steam to accumulate in the dome or chamber 19 above the upper larger piston 27. In the upper position of the parts, the upper piston 27, as shown in Figure 2, will mask the outlet port 28 and prevent the evacuation of this accumulated pressure in the dome or upper chamber 19. Furthermore the solid portion of the stem will obstruct a through passage past the ports 7 and 8 and will cut off communication between the central chamber 3 and the passage 9.

As soon as the throttle is closed and the locomotive begins to drift, the pressure beneath the lower piston 14 at once falls and the accumulated pressure in the dome or upper chamber 19 becomes effective to drive

the pistons down to the position shown in Figure 8. The annular groove 35 in the stem registers with the ports 7 and 8 and saturated steam, which is received in the chamber 3 from the boiler, is permitted access to the passage 9 and to the steam chests and cylinders of the locomotive. Through the connections 10 and 12 the saturated steam is supplied to the valve chests at both sides of the locomotive and this saturated steam breaks the vacuum, moistens the parts and keeps the same heated.

In the lower position of the parts the upper port 41 of the stem 29 registers with the oil passage 32 and receives oil from the lubricator 71, introducing oil to the bore 30 of the stem 29. The oil driven down by two hundred pounds steam pressure from the lubricator 71 is forced out of the ports 34 at the base of the stem. These ports are numerous as indicated in Figure 8 and are small in diameter and they form a choke. The oil gets out through the port 15 and mixes immediately with the saturated steam by which it is carried to the locomotive parts.

When the locomotive is slowing to a stop the slow movement of the locomotive pistons makes it impossible for the parts to use up the saturated steam being delivered to the same and consequently a back pressure occurs beneath the lower piston 14 raising the parts again to the position shown in Figure 2, it being understood that the accumulated pressure in the upper chamber 19 has escaped through the port 28 to the atmosphere during the previous lower position of the piston 27. This back pressure is of course evacuated when the locomotive is brought to a complete stop and the saturated steam pressure from the central chamber 3, having access beneath the upper larger piston 27 will hold the parts in the raised position.

What is claimed is:

1. An attachment for locomotives comprising a casing having cylinders therein in communication at their outer ends with the steam chest pressure of the locomotive, said casing also having a chamber therein in communication with a source of saturated steam supply from the locomotive, said chamber being in communication with the inner portions of said cylinders, pistons in said cylinders, a stem connecting said pistons, said casing also having a passage communicating with the locomotive steam chest and adapted to connect with said chamber but being cut off therefrom by said stem when the throttle valve is open, said stem having a cut out portion for setting up a communication between said chamber and said passage when the stem is shifted due to lack of pressure in the valve chests, and means whereby the steam chest pressure

4
may accumulate and be trapped upon the outer face of one of the pistons whereby to become effective when the steam chest pressure falls for moving the pistons and valve stem.

5. A locomotive attachment comprising a casing having a chamber in communication with the steam dome of a locomotive, said casing further having cylinders therein in communication with the chamber at their inner portions and in communication with the locomotive steam chest pressure at their outer portions, said casing having a passage connecting with the steam chests of the locomotive and with said chamber, pistons in the cylinders, a stem connecting said pistons and adapted in one position to shut off the communication between said chamber and passage, and means for holding and trapping the accumulated steam chest pressure upon the outer face of one of the pistons whereby to shift the pistons and the valve stem to a position for opening communication between said chamber and passage when the throttle is closed.

6. An attachment for locomotives comprising a casing having cylinders and a chamber in communication with the inner portions of said cylinders, means for supplying said chamber with saturated steam, means whereby the outer portions of said cylinders are in communication with the locomotive steam chest pressure, pistons in said cylinders, a valve stem connecting said pistons and having a cut out portion, a barrel extending about said stem and having registering ports normally cut off by said valve stem but opened by the cut out portion thereof, one of said ports connecting with the chamber, said casing having a passage connecting with the other port and with the steam chests of the locomotive, means for accumulating and trapping the steam chest pressure against the outer face of one of said pistons whereby to shift the pistons and stem to a position where the cut out part registers with said ports as soon as the steam chest pressure falls, the cylinder of said piston having the trapped pressure thereagainst having a vent normally masked by said piston but uncovered by the piston when the steam chest pressure falls to permit evacuation of said trapped pressure.

7. A locomotive attachment comprising a casing having cylinders therein in communication at their outer ends with the locomotive steam chest pressure, said casing also having a chamber in communication with steam at boiler pressure, said chamber communicating with the inner portions of said

cylinders, means for trapping the accumulated steam chest pressure at the outer portion of one of the cylinders, pistons in said cylinders, a hollow valve stem connecting with said pistons and having outlet ports at its lower end for communicating with the locomotive steam chest, said valve stem having a transverse port, said casing having passages with which said transverse port is adapted to register in one position of the stem, one of said passages being connected with the locomotive lubricator, the other passage being connected with the locomotive steam supply pipe, said stem also having a port adapted to connect the lubricator passage with the interior of the hollow stem when said stem is shifted to a second position, said casing having a passage communicating with the locomotive steam chests and adapted to connect with the chamber when said valve stem is in one position only.

8. A locomotive attachment comprising a casing having a chamber in connection with a source of steam and cylinders of unequal diameters in connection at their inner ends with the chamber and at their outer ends with the locomotive steam chest pressure, a barrel extending through said casing and having opposed ports, one of said ports connecting with the chamber, said casing having a passage connecting with the other port and with the locomotive steam chests, a hollow valve stem fitted to reciprocate in said barrel and adapted to cut off communication between the ports in one position but having a cut out portion for registering with the ports in a second position, said valve stem having numerous small openings communicating with the interior thereof and opening on the exterior of the valve stem above one of said pistons, said cylinder of the last mentioned piston having an opening in the said passage to permit the discharge of oil thereinto, said casing having passages, a lubricator connecting with one passage, means for connecting the other passage with the locomotive steam supply pipe, said valve stem having a transverse port adapted in one position to register with the passages, said valve stem having a further port adapted in another position of the valve stem to set up communication between the lubricator passage and the interior of the valve stem, and means for trapping accumulated steam chest pressure upon the outer face of one of the pistons.

In testimony whereof we affix our signatures.

CHARLES STERN.
RICHARD WALLACE BRADEN.
